UNITED STATES PATENT OFFICE.

HERRMANN BERG, OF PHILADELPHIA, PENNSYLVANIA.

DESIGN FOR BED-COVERLETS.

Specification forming part of Design No. 6,325, dated December 24, 1872.

To all whom it may concern:

Be it known that I, HERRMANN BERG, of the city and county of Philadelphia, State of Pennsylvania, have invented a new and useful Design for Bed-Coverlets; and I do hereby declare the following to be a clear and exact description of the nature thereof, sufficient to enable others skilled in the art to which my invention appertains to fully understand the same, reference being had to the accompanying photograph, which fully illustrates my invention.

The design consists of the several figures in many colors.

The circles *a* may represent crimson; crosses *b*, light blue; dots *c*, black; waves *d*, dark blue; checkered lines *e*, dark green; dots *f*, dark cinnamon; lines *g*, light cinnamon; and so on, the blank portion being the ground, which is generally white.

My design may be produced by the following process, but this is not an essential part of the invention: The warps having been

properly arranged, the ground pick is first thrown; then, by means of the harness, the warps are shifted and the first color run through, and all of that color of the respective figure in the line will be brought out on the surface; then shift the warps and run through the next color, and so on with the rest. Having run through all of the picks, the "take-up" occurs—that is, the winding on the cylinder of the coverlet, which has progressed the dimensions of one pick. The warps being shifted, the next line is woven, the several picks being thrown as before, and so on throughout; and the result will be a coverlet of most gorgeous pattern.

What I claim is—

The design for bed-coverlet, as set forth and illustrated.

HERRMANN BERG.
